UNITED STATES PATENT OFFICE.

JOHN W. HALTERMAN, OF WILLOWS, CALIFORNIA.

MECHANICAL RAZOR.

1,332,553.

Specification of Letters Patent. Patented Mar. 2, 1920.

Application filed November 2, 1916. Serial No. 129,105.

To all whom it may concern:

Be it known that I, JOHN W. HALTERMAN, a citizen of the United States, residing at Willows, in the county of Glenn, State of California, have invented certain new and useful Improvements in Mechanical Razors; and I do declare the following to be a full, clear, and exact description of the same, reference being had to the accompanying drawings, and to the characters of reference marked thereon, which form a part of this application.

This invention relates to improvements in razors, the object of the present invention being to produce a mechanical razor of a vibratory or reciprocatory type in which there are two cutting edges each provided with minute teeth. These blades are arranged to vibrate very slightly but in a very rapid manner. The cutting edges co-act in such a manner as to shear the hair off at the lowest possible point at which the ordinary manually operated razor could possibly engage and cut the hair. This latter action I accomplish by means of making the teeth of the cutting edges of only that depth and breadth approximately equal to the diameter of a hair.

The razor is provided with a guard or other means which smoothes the skin out ahead of the razor so it may slide the more easily over the skin. When the skin resumes its normal position after the razor has been used, a microscopic examination of the same will show the hair to be cut off evenly with or slightly below the actual surface of the skin.

The teeth of my improved cutting edges while very minute in size will be built of very substantial and lasting material and will be almost indestructible because of the extremely easy shearing of the hair and the relatively great strength of the cutting edges which will be of tempered steel. The teeth are so very minute that the contact of the same with the skin seems almost continuous and the feeling of the cutting edges against the skin is not unlike that of the ordinary type of manually operated razors.

A still further object of the invention is to hold the blades in proper relative position by a rigid adjustment which fixes or determines their exact movement without having any tension between the two. This will relieve the strain which would be continuous if a spring tension means were employed.

I am well aware that two co-acting toothed shearing blades have been used in many forms of shearing devices, particularly barber's clippers and the like. None of these however have ever been adapted to the purpose of shearing the hairs of the face as efficiently as can be done with manually operated razors. After a great deal of careful study, I have discovered that by constructing two razor blades with my new teeth and arranging to vibrate the blades slightly but very rapidly with respect to each other, and by having the teeth of substantially the same diameter as the average hairs to be cut, that this form of structure is very efficient for the purpose of shaving the face with a shearing action on the hair. Also the operation can be performed so as to cut the hairs at the lowest possible point at which the present commonly used form of razor cuts the same.

These objects I accomplish by means of such structure and relative arrangement of the parts as will fully appear by a perusal of the following specification and claim.

In the drawings similar characters of reference indicate corresponding parts in the several views.

Figure 1 is a side elevation of the complete razor.

Fig. 2 is an end view of the same.

Fig. 3 is a sectional view taken on a line X—X of Fig. 2.

Fig. 4 is an enlarged view of the cutting teeth on the cutting blades.

Fig. 5 is a sectional view taken on a line Z—Z of Fig. 4.

Referring now more particularly to the characters of reference on the drawings, I have provided first a handle member 1 which may be of any desired shape, but preferably cylindrical, which handle, at its outer end, is provided with a plug 2 having an outwardly projecting lug 2^a integral therewith.

The numeral 3 designates one of the shearing blades which is provided with small teeth 4 along its lower edge. This blade 3 is fixed stationary with respect to the handle 1 by means of small screws 5 engageable with the lug 2^a.

Mounted adjacent the blade 3 is a blade 6 which is provided with teeth 7 along its lower edge arranged to co-act with the teeth 4. The teeth 4 and 7 will be very minute so that the depth and breadth of the teeth

will be approximately of a size equal to the diameter of the average hairs to be cut. The sides of the teeth will slope slightly inwardly from their inner to their outer ends as shown 5 clearly in Fig. 4. This will cause the co-acting teeth to cut the hairs in a sort of shearing action similar to the action of shears, scissors and the like.

The blade 6 is slidably mounted upon the 10 blade 3 by means of a substantially V-shaped projecting flange 8 which fits into a corresponding groove 9 cut into the blade 6, such structure permitting the blade 6 to be moved in a reciprocating or vibrating movement 15 relative to the blade 3. This motion is given to the blade 6 by means of the following structure, namely:

The numeral 10 designates the driving shaft which may be operated from any suitable 20 source of power found desirable either manually or by mechanical means. At its inner end the shaft 10 is provided with a small pin 11 which is disposed at an eccentric point on the shaft 10 and projects centrally 25 through a small block 12 movable in an elongated slot 13 in the member 6. By reason of the eccentric relation of the parts the rotary motion of the shaft 10 imparts a reciprocating or vibrating motion to the 30 blade 6. This action causes the teeth 7 to move rapidly adjacent the teeth 4.

The blade 3 is set at right angles to the handle member 1 while the outside vibrating blade 6 is set at a slight angle so that 35 the teeth may be adjusted to come adjacent each other at their tips only. This adjustment is controlled by the screws 14 fastened into the blade 3 and projecting through a slot 15 provided in the blade 6. By tightening 40 the screws 14 the teeth may be brought more nearly adjacent each other, the slot 15 allowing of the movement of the blade 6 as desired.

A guard 16 is secured on the blade 3 adjacent 45 the teeth 4 and curves slightly as shown. The distance between the device and the guard 16 and the teeth 4 may be adjusted by means of a screw 17 fastened into the blade 3. By turning the nut 18 upon the 50 screw 17 the guard may be positioned as desired.

With the rotation of the shaft 10 the blade 6 moves at a high rate of speed back

and forth so that the shearing teeth 7 contact with the shearing teeth 4 to cut the hairs 5 in the manner fully described in the preamble to this specification.

By having the blades 3 and 6 independent of and removable from the holder or frame and driving mechanism this allows the cutting parts when worn out to be easily and inexpensively replaced with new ones. The rigid adjustment between the blades as shown holds them to their proper position without any tensional strain which would be 6 continuous if spring tension or similar adjusting means were provided to hold the blades together.

While this specification sets forth particularly the description of a razor having one 70 fixed and one movable blade, still in practice both blades may be made movable if desired, so I do not wish to be understood as confining myself to the identical fixed and movable blade herein described. The main 75 advantage of the invention is in the fact of having the coöperating teeth act as shears and be operated at a high rate of speed in order to cut the hair quickly and efficiently without pulling the same.

From the foregoing description it will readily be seen that I have produced such a device as substantially fulfills the objects of the invention as set forth herein.

While this specification sets forth in detail the present and preferred construction of the device still in practice such deviations from such detail may be resorted to as do not form a departure from the spirit of the invention as defined by the appended claim. 90

Having thus described my invention what I claim as new and useful and desire to secure by Letters Patent is:

In combination with a mechanical razor having a holder, a fixed blade on the end of 95 the holder and another blade co-acting therewith and mounted for reciprocatory movement relative thereto, adjustment screws passing through both blades adjacent their cutting edges whereby the latter are held 100 in adjustable spaced relation with regard to each other, the rear edges of the blades being swivelly tongue-and-grooved with each other.

In testimony whereof I affix my signature. 105
JOHN W. HALTERMAN.
